SAFETY TUBE SEAL AND PROCESS OF
ITS MANUFACTURECharles J. Westin, Philadelphia, Pa., assignor to
F. J. Stokes Machine Company, Philadelphia,
Pa., a corporation of Pennsylvania

Application April 25, 1933, Serial No. 667,824

12 Claims. (Cl. 113—121)

This invention relates to improvements in collapsible tubes and particularly to a new and useful improvement in collapsible tube closures and the method of making same.

- 5 Collapsible or flexible tubes are used as dispensing containers for fluids or pasty materials such as toilet creams, medicinal ointments, foods, extracts, etc. The tubes are usually made of some suitable soft metal or alloy, but may also be 10 made of a flexible or resilient material such as cellulose, or other synthetic compounds. Each tube is comprised of a body portion with a relatively thin wall. One end of the tube is formed into a neck having a discharge opening and provision for receiving a cap. The other end of the tube is left open until the tube is filled and then closed by means of folds or tucks made in the flattened out portion of the tube walls adjacent to the open end.
- 15 Heretofore, it has been the practice to make the closure by folding and bending the flattened end of the tube two, three, or more times and in many different ways, the fold usually extending completely across the flattened part of the tube, 20 and to reinforce and strengthen these folds reverse bends or tucks have been resorted to or, after the folds were made, the corners have been bent reversely, diagonally across the original fold.

In a large number of tests conducted with various types of tube closures I have found that the 25 majority of leaks occur at the ends of the fold. Close inspection of the tubes indicates that, when the walls are flattened, the stiffness and resiliency of the material causes an opening to be formed at the crease, as indicated in the enlarged section (Fig. 4). This opening provides a ready passage for the breathing caused by temperature and climatic changes as well as the 30 large number of leaks occurring at low pressures.

35 While this is partly eliminated in tubes that have been cemented on the inside or coated with some form of latex, it is evident that any excess of cement or latex is squeezed out when the pressure is applied in flattening the tube walls 40 and there are no means possible of forcing this back to fill the crevice formed if and when the walls separate at the crease after the pressure is removed.

45 For a better understanding of the features of particular interest in this description the folds are referred to as elements of the tube closure, comprising two thicknesses of the flattened wall of the tube. By a tube referred to as having a dry closure is meant a tube being closed without 50 the use of any type of cement or latex on the

wall of the tube or between the elements of the fold. By a heat sealed tube is meant one in which a thermal-plastic cement is used on the wall of the tube and between the elements of the fold, and the sealing is effected by the application of heat after the folds are made. By a cement-sealed or wet tube closure is meant a tube that, in or during the process of filling and closing has some form of cement applied in liquid or plastic form, and as the folds are completed 10 the cement is placed between them and forms a strong bond between the elements of the fold.

15 In tubes sealed by having cement applied to the outside, but between the elements comprising the fold, I have found that the cement may not be of sufficient quantity or it may not cover an area large enough to furnish adequate bond, even when caps of cement are formed over the side ends of the fold to give the required strength for high pressures and resistance against leaks, 20 so desirable in many cases.

25 The purpose of this invention is to provide a tube having such a closure that the passage referred to above is safely eliminated regardless of the type of closure used; dry or cemented. I have found it a decided advantage to bend the corners over as shown in the drawings before making the standard fold in closing a tube. I have thus added an extra fold or element to the closure without having to add any additional 30 material in the length of the tube. Incidentally, this extra diagonal fold brings the hazardous corner away from the ends of the folds and increases the area of the bonded surface between the elements of the fold. It provides a crease 35 diagonally across the passage referred to and places the terminal point of the original crease in the flattened wall a considerable distance from the end of the fold and hides this terminal point inside of the folds.

40 I have found that tucking the corners in is of decided advantage not only when cement sealing tubes but also when dry sealing, as it adds considerable to the resistance against leaks even in the old type of tube closure. It is evident that this type of safety fold of the corners may be used to advantage with any type 45 of tube closures such as those using an extra reinforcing clip or those resorting to loop folding and reverse bends or to the type using extra tucks and folds as described in Patent No. 1,852,225, granted to me on April 5, 1932, or my co-pending application Serial No. 641,533.

50 For a further exposition of my invention reference may be had to the annexed drawings and 55

specification at the end of which my invention will be specifically pointed out and claimed.

In the drawings,

Fig. 1 is a diagrammatic view in side elevation.

5 Fig. 2 is a partial view in side elevation.

Fig. 3 is a diagrammatic face view.

Fig. 4 is a cross section on line 4—4 of Fig. 1.

10 Figs. 5, 6 and 7 are respectively face, side and face views illustrating the steps of the process.

Figs. 8, 12 and 16 are face views.

Figs. 9, 10, 11, 13, 14, 15 and 17 are side views illustrating the steps of another process.

15 Figs. 18 and 19 are respectively face and end views of a modification, and

Figs. 20 and 21 respectively are face and side views of another modification.

Referring to the drawings:

Fig. 1 is a side view of a collapsible tube 1 having the walls flattened at 35. Fig. 2 shows a side view of a tube having the corner bent at 36. Fig. 3 shows a face or front view of the tube with the corner bent at 36. Fig. 4 is a section on line 4—4 of Fig. 1 and shows the openings or passages along the flattened portion of the tube at 38. Fig. 5 shows a front view of a tube in which the corners 36 have been bent further so as to form an angle of approximately 45 degrees with the standing part 35 of the tube 30 wall. The standard first fold is usually made along the imaginary line 40 and the second fold along the line 41. Fig. 6 represents a diagrammatic view showing a tube having the first fold partly made at 40 and the element 42 taking 35 the position of about 45 degrees with the standing part 35 of the tube. The corner-fold 36 is shown here taking the position indicated at 39. This view also shows one way of applying a sealing cement to the elements of the fold, which

40 here is indicated at 43 representing a brush or a spray nozzle. Fig. 7 shows a front view of the tube in the same position and at the same point in the process as in Fig. 6. Fig. 8 is a front view in which the corner-fold along the line 37 has 45 been completed so that the corner 44 is pressed tightly against the standing part 35 before the first fold along line 40 has been started. Fig. 9 is a side view of the tube in the same position and at the same point in the process as in Fig. 8. Fig. 10 shows the first bending along line 40 of the first fold which in this case may be considered as a second fold or the second element of the closure. Fig. 11 shows this second element bent closer towards the standing part 35 so as 50 to form an angle of approximately 45 degrees into which a sealing cement may be applied by means of a nozzle or a wiper or spray gun or brush. Fig. 12 is a front view and Fig. 13 a side view of the completed first fold showing the corner fold or first element at 44, showing the second fold or element at 47, and showing the terminal or end of the tube at 7, the first two elements being pressed tightly against the standing part 35 of the tube. Fig. 14 is a side view 55 showing the tube walls being bent at the line 41 in the process of forming the third element of the closure. Fig. 15 is a side view showing the continuation of the bending at 41 to form the third element so as to at this point form an angle of approximately 45 degrees with the standing part 35 of the tube. Into this angle cement may be applied by anyone of the means referred to and here represented by a spray nozzle or like device at 49. Fig. 16 shows a face

view of the completed closure and Fig. 17 a side view of the same. These figures show the finished closure flat at 50 without any form of crimp or corrugation. Fig. 18 is a face view and Fig. 19 an end view showing a finished closure which has been provided with crimps or corrugations at 51 and 52. Fig. 20 is a face view and Fig. 21 an end view of a tube to which a clip or reinforcing member 60 has been applied.

I do not intend to be limited in the practice of my invention save as the scope of the prior art and of the attached claims may require.

I claim:

1. A collapsible tube having one end sealed by a flattened portion, corners tucked in on diagonal lines, cement surrounding said tucked in corners, and a fold surrounding said tucked in corners.

2. A collapsible tube having one end sealed by a flattened portion, corners tucked in on diagonal lines, cement surrounding said corners, a fold surrounding said corners, and a second fold surrounding said first mentioned fold.

3. A collapsible tube having one end sealed by a flattened portion, corners tucked in on diagonal lines, a fold surrounding said corners, a second fold surrounding said first mentioned fold, and indentations formed in said folded end.

4. A collapsible tube having one end sealed by a flattened portion, corners tucked in on diagonal lines, cement surrounding said corners, a fold surrounding said corners, a second fold surrounding said first mentioned fold, and indentations formed in said folded portion.

5. A collapsible tube having one end sealed by a folded portion, corners tucked in on diagonal lines, a fold surrounding said corners, a second fold surrounding said first mentioned fold, and a clip of relatively rigid material surrounding said second mentioned fold.

6. A process of sealing one end of a collapsible tube which consists in flattening one end of said tube, bending in the corners of said flattened portion on diagonal lines, applying cement to said corners, and folding the end of said flattened portion about said corners.

7. A process of sealing one end of a collapsible tube which consists in flattening one end of said tube, bending in the corners of said flattened portion on diagonal lines, applying cement to said corners, folding the end of said flattened portion about said corners, and folding another part of said flattened portion about said first mentioned fold.

8. A process of closing one end of a collapsible tube which comprises flattening one end of said tube, bending in the corners of said flattened portion on diagonal lines, folding the end of said flattened portion about said corners, folding another part of said flattened portion about said first mentioned fold, and producing indentations in said folded portion.

9. A process of closing one end of a collapsible tube which consists in flattening one end of said tube, folding in the corners of said flattened portion on diagonal lines, applying cement to said corners, folding the end of said flattened portion about said corners, folding another part of said flattened portion about said first mentioned fold, and producing indentations in said folded portion.

10. A process of closing one end of a collapsible tube which comprises flattening one end of said tube, bending in the corners of said flattened portion on diagonal lines, folding the end of said

flattened portion about said corners, and applying a clip of relatively rigid material to said fold.

11. A process of closing one end of a collapsible tube which comprises flattening one end of said tube, tucking in the corners of said flattened portion on diagonal lines, folding the end of said flattened portion about said corners, folding another part of said flattened portion about said first mentioned fold, and applying a clip of relatively rigid material to said folds.

12. A closure for a collapsible tube, said closure being adapted to withstand considerable

5 manual handling and comprising in combination, a flattened portion of the walls of said tube in confronting relation, corners of said flattened portion bent on diagonal lines so that the edges formed from the open end of the tube are approximately parallel to the axis of the tube, a fold formed in said flattened portion of the tube and surrounding and enclosing said bent corners, and a coating or layer of cement surrounding said corners and filling the inner surfaces of said fold 10 to retain said fold closed.

CHARLES J. WESTIN.
